UNITED STATES PATENT OFFICE.

DAVID H. BAKER, OF JERSEY CITY, NEW JERSEY.

IMPROVED MODE OF LOCKING RAILROAD-CAR SEATS.

Specification forming part of Letters Patent No. 13,753, dated August 9, 1864.

To all whom it may concern:

Be it known that I, DAVID H. BAKER, of Jersey City, in the county of Hudson and State of New Jersey, have invented, made, and applied to use a certain new and useful Improvement in Means for Locking Railroad-Car Seats; and I do hereby declare the following to be a full, clear, and exact description of my said invention, reference being had to the annexed drawings, making part of this specification, wherein—

Figure 1 is an elevation of the arms of two seats next the outside of the car, with the backs locked in place. Fig. 2 is a similar view with the backs unlocked and free to be turned over, and Fig. 3 is a section of a modification of my locking device.

Similar marks of reference denote the same parts.

Car-seats have heretofore been locked in position (so that the backs could not be turned over) by a separate lock applied to each arm. In this instance the attendant has to unlock each seat before turning the back over, which involves considerable trouble, and most of these locks are self-acting and spring into place, holding the backs, hence such backs cannot be left unlocked and free to turn.

The nature of my said invention consists of a locking-bar extending the whole length of the car, or of several of the seats, and capable of being moved so as to lock or unlock at one operation all the seats included within the length of such bar, whereby the backs can be unlocked simultaneously, and so remain until turned over, or until the passengers are seated, and then said backs can be locked in the position they may stand (regardless of which way they may be turned) by one movement of such bar.

In the drawings, *a a* represent the arms of the car-seats that are affixed to the sides of the car. *b b* are the backs of the seats; *c c*, the back irons or links by which such backs are connected to the center studs, *d d*, and on which the backs move or swing when being turned over or changed. These parts may be

of any usual or desired construction. *e e* represent the usual stops receiving the irons *c c*. *f* is a bar fitted in the arms *a a*, or in the side of the car. In cases where the arms are not provided at the outer ends of the seats, and at *i i*, are L-shaped notches in said bar, receiving pins projecting from the iron *c c*, or the pins may be on the bar *f* and the L-shaped notches in the iron *c c*, as seen at *g g*.

By reference to Fig. 2 it will be seen that these pins and notches are so located that the backs of the seats can be freely turned over or changed; but if the bar *f* receives an end-wise motion the respective pins entering the horizontal parts of the L-shaped notches will hold the backs in position and prevent their being changed.

Any suitable means may be employed for giving an end motion to the bar *f* and for locking the same. I have shown a lever, *h*, for moving, and a box-lock, *k*, the bolt of which enters a notch in the bar *f*, for locking said bar stationary in either position.

Fig. 3 shows a modification in the mode of locking, in which the bar *f* is provided with hooked arms *o* near each of the arms *a*, so that by giving a partial rotation to such shaft or bar *f* the hooks will be turned away from or over each of the irons *c c*, and prevent the back being turned over or changed.

What I claim, and desire to secure by Letters Patent, is—

A movable locking-bar, extending along the car the distance of several seats and fitted with pins, hooks, or slots, substantially as specified, in combination with the movable backs of the seats and the locking device, whereby said backs can be all locked or unlocked simultaneously by moving the said bar, as set forth.

In witness whereof I have hereunto set my signature this 2d day of October, A. D. 1863.

DAVID H. BAKER.
